UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 34,736, dated July 2, 1901.

Application filed June 6, 1901. Serial No. 63,472. Term of patent 7 years.

To all whom it may concern:

Be it known that I, WILLIAM T. SMITH, a citizen of the United States, residing in Philadelphia, Pennsylvania, have invented and 5 produced a certain new and original Design for a Woven Fabric, of which the following is a specification.

My design is shown in the accompanying drawing, which represents sufficient of the 10 pattern to illustrate the design, the remainder of the pattern being merely a repetition of what is shown.

The design comprises the figures 1 and 2. The figure 1 has a central ornament 3, with 15 a zigzag border composed of bands of different colors or shades of color, the outer portion or border of the figure being composed of similar bands, but the outermost band of the se-

ries having straight external outlines. The figures 2 each comprise a zigzag bordering- 20 band inclosing a field in which are geometrical figures 4 and 5.

Having thus described my invention, I claim and desire to secure by Letters Patent—

The design for a woven fabric, substantially 25 as described and as shown in the accompanying drawing.

In testimony whereof I have signed my name to this specification in the presence of 30 two subscribing witnesses.

WILLIAM T. SMITH.

Witnesses:

HARRY BLOCK,
WM. H. MACMUNN.
